[57] CLAIM

The ornamental design for a cane, as shown and de-
scribed.

DESCRIPTION

FIG. 1 is a side elevational view of a cane showing my
new design. The reverse side of my new design is a
mirror image of the side illustrated.

FIG. 2 is a cross-sectional view thereof taken along line
2—2.

FIG. 3 is an enlarged fragmentary view of the design as
shown in the encircled portion of FIG. 1, as indicated
by the arrow 3.
